DOBBY LEVER.

Application filed October 21, 1925. Serial No. 63,902.

The present invention relates to an improvement in dobbey levers.

The object of the invention is to produce an improved construction of dobbey lever, inexpensive in form and convenient in use. The invention consists in the dobbey lever hereinafter described and particularly defined in the claims.

In the accompanying drawings illustrating the preferred form of the invention, Fig. 1 is a side elevation of the dobbey lever and associated parts; Fig. 2 is a longitudinal sectional elevation of the end of the dobbey lever; Fig. 3 is an edge view of the two parts of the dobbey lever separated; Fig. 4 is an edge view of the dobbey lever with the fingers in position; and Fig. 5 is an enlarged side elevation of the end of the lever.

The illustrated embodiment of the invention is described as follows: The dobbey lever 1 is carried by the jack 2, being pivoted at its center thereto, and at the end of each dobbey lever there are pivotally attached dobbey hooks 3 and 4. The dobbey fingers 5 and 6 raise and lower the dobbey hooks, the former through the intervention of the push rod 7, and the latter by direct engagement with the hook. The dobbey girts are shown at 8 and 9.

Each dobbey lever consists of two sheet metal plates or pieces, each exactly like the other. The plate or member 10 is exactly like the plate or member 11, but is associated with it in reverse position. The ends of the plates are provided with pintle holes 12 and 13, which receive the pintles 14 of the hooks 3 and 4. Each plate or member is provided with an offset bend 15, to offset it from the straight portion of the other plate or member when they are laid together, as shown in Fig. 4. Each plate or member is provided with a key-hole 16 and with a key 17 near its ends. These keys are rotatably secured in the members or plates 10 and 11, and when turned into the position shown in Fig. 3, they register with the key holes 16 so that the two plates may be moved into close contact with each other, as shown in Fig. 4. These keys are secured to the plates by rivets 18.

The offset of each lever member is of such thickness that when it is associated with the other member, the space between the offset end and the straight end of the other member is somewhat greater than the thickness 55 of the hook lever at that point, so that the hook lever is not bound between the ends of the members of the lever, but is freely supported upon its pintle therein. The location of the keys and key-holes near the ends of 60 the lever secures the members together near the point where the hooks are attached, so as thereby to secure the stiffening effect of the key and key-hole at the point where it is desirable the lever should be held, so that 65 the two jaws of the end of the lever are supported and held apart a proper distance to freely carry the hooks.

The dobbey lever and its associated hooks are assembled by laying one plate 10 upon the table, placing the pintles of the two hooks in the holes 12 and 13, then laying the other plate 11 on the first, so that the holes 13 and 12 embrace the other ends of the pintles of the hooks. Then the keys are 70 turned into the position shown in Fig. 5. The space between the key 17 and the surface of the plate to which it is attached by the rivet 18, is a tight fit to receive and tightly hold the metal of the other plate, so 75 that when turned to the position shown in Fig. 5, they hold fast in such position by friction. It is a simple matter to renew the hooks or to renew the levers when occasion or wear demands. By simply removing the 80 lever and hooks from the machine and turning the keys 17 through an angle of 180°, the members 10 and 11 come freely apart, and new levers may be substituted on the 85 old hooks, or new hooks may be substituted for the old hooks, and the parts re-assembled and securely united together again by turning the keys into locking position.

Having thus described the invention, what is claimed is:

1. A dobbey lever for looms consisting of two similar members or plates associated together symmetrically, each provided with an offset at one end, a key-hole near one end, and a key near the other end adapted 100

to enter the key-hole of the associated plate when in assembling position to be turned to lock the parts together.

2. A dobby lever for looms consisting of two plates touching each other from near one end to near the other end, the lever being provided near each end with a key in one plate and a key-hole in the other plate

for uniting the plates of the lever together at their ends, and the ends of the plates being shaped to receive between them the ends of the dobby hooks. 10

In witness whereof I have signed my name to this specification.

JONAS NORTHROP.
